W. LESCHMAN

SWITCHING SOCKET

Filed Nov. 12, 1925

UNITED STATES PATENT OFFICE.

WILLIAM LESCHMAN, OF CHICAGO, ILLINOIS, ASSIGNOR TO CHICAGO ELECTRIC MANUFACTURING CO., OF CHICAGO, ILLINOIS, A CORPORATION OF ILLINOIS.

SWITCHING SOCKET.

Application filed November 12, 1925. Serial No. 68,724.

My invention relates to lamp sockets in which the circuit is switched on and-off by rotational movements of a handle projecting from the rear end of the socket, its general objects being those of providing an unusually simple, inexpensive, easily wired and easily assembled socket of this class.

More particularly, my invention provides a switching socket in which the conductors 10 engaging the lamp bulb terminals are mounted in an insulator which is slidably insertible in the shell of the socket and in which the rear end of the shell normally extends into a handle adapted to be attached 15 or detached from the shell without the use of tools; in which the circuit wires can readily be attached to the said conductors before the insulator is slid into the shell; in which these wires extend through a handle 20 carrying a pin or the like which serves both for locking the insulator against rotation with respect to the handle and for interlocking the handle with the socket shell in either its circuit-closing or its circuit-opening position; in which simple spring means cooperate 25 with other features of construction in releasably securing the lamp-bulb and the handle to the socket shell, and in yieldingly holding the rotatable socket parts in either their "on" or "off" positions; in which a single spring insertible from the forward end of the handle affords such spring means, and in which a similarly insertible insulating washer suitably distributes the pressure 30 of the spring so as to hold the said conductor firmly engaged with the terminals of the lamp bulb.

Moreover, my invention provides a switching socket of the said general type suitable 40 for use with a reflector and requiring only the suitably notched metal shell of the socket to be secured to the reflector, while all of the other parts are manually attached to, and detachable from, this socket shell.

Still further and also more detailed objects 45 will appear from the following specification and from the accompanying drawings, in which

Fig. 1 is a fragmentary central, vertical 50 and longitudinal section through a spot lamp including a switching socket embodying my invention.

Fig. 2 is an enlargement of the central portion of Fig. 1, with the socket shell and the pressure-distributing insulating washer

in central section, and with a portion of the main insulator and of one of the wire terminals also in section.

Fig. 3 is an enlarged elevation of the socket shell alone. 60

Fig. 4 is a front elevation of the insulating washer.

Fig. 5 is an enlarged transverse section, taken along the line 5-5 of Fig. 1.

Fig. 6 is a reduced transverse section 65 taken through Fig. 2 along the line 6-6.

Fig. 7 is a perspective view of the body member of the socket.

In the illustrated embodiment, I am showing my switching socket as used in connection with a double-pole lamp bulb 1 having two terminals 2 and 3 exposed at the rear end, this bulb having its major portion housed by a lamp housing which includes a frontal lens 4 and a rear reflector 5. Clinched to the reflector at its usual axial perforation and in axial alinement with this perforation is a supporting collar 6 which extends through the clamp 7 of a supporting bracket. 70 75

Extending into this collar 6 from the rear thereof is a cylindrical socket shell 8 provided at its forward end with the usual bayonet slots 9 for interlocking with the usual lateral pins 10 on the base of the lamp bulb, this shell and the collar 6 being both held in fixed positions with respect to the supporting bracket 7 by a screw 11 which is threaded through the bracket and which extends through a perforation in the collar into clamping engagement with the socket shell 8 as shown in Fig. 1. 80 85

Slidably inserted into the socket shell 6 from the rear thereof is an insulating body which includes an insulating cylinder 12 slightly smaller in diameter than the bore of the shell 6 and having a longitudinal groove 31 on one side as shown in Fig. 7. Mounted in this insulating cylinder and projecting slightly beyond the forward end thereof are two wire terminals or conductors 13 and 14, each of which is disposed in a bore extending longitudinally through this insulator and each of which has its rear end bored out for receiving the end of one of the circuit wires. 90 95

Wire binding screws 15 and 16 extend transversely of the insulator respectively through the said bored ends of the two conductors, as shown in Fig. 8, so as to secure the circuit wires 17 and 18 respectively to the two con- 100 105 110

ductors, and each of these screws also anchors the adjacent conductor to the insulator.

The socket shell 6 has near its rear end a circumferentially extending transverse slot 19 connected at one end to an entrance slot 20 leading longitudinally of the shell to the rear end of the latter. This entrance slot serves for admitting a pin which projects into the bore of the handle 22 of my device, so that the pin can enter the transverse slot 19 into which it normally extends. This handle bore, which normally houses the rear portions of the shell 6 and of the main insulator 8, also houses a spiral compression spring 23 disposed for pressing the insulator 8 forwardly. To insure an easy sliding of the shell in the bore of the handle (which desirably is made of wood) I line the handle bore with a tubular metal lining 24, and to prevent the spiral spring from jamming between this lining and the insulator 8, I interpose between the latter and the spring an insulating washer 25. The washer 25 has a pair of perforations 26 through which the wires 17 and 18 extend and also has a peripheral notch 27 which will clear the pin 21 when the washer is inserted in the bore of the handle from the front end of the latter. With my socket thus constructed, only the slotted shell of Fig. 3 needs to be attached to the support, while all of the other parts can be assembled manually and are held in operative position by the single spring which is twisted past the inwardly projecting portion of the pin 21 when inserting it in the handle and is retained within the handle by this pin. In installing a thus equipped lamp, the handle is first rotated so as to bring the pin into the rearward enlargement 28 of the transverse slot 19, its movement in that direction being stopped by the forwardly extending finger 29 between this slot enlargement and the entrance slot 20. Then, a forward movement of the handle followed by a further rotation of the latter in the same direction (which would be clockwise in Fig. 5) brings the pin into the entrance slot 20, so that the handle can be rearwardly drawn off the socket shell. This leaves the main insulator 12 loose, so that the latter can be taken out of the handle for attaching it to the ends of the wires which are both drawn for this purpose through the contracted rear end portion 30 of the bore in the handle and respectively through the perforations 26 in the insulating washer 25. On pulling the exposed wire portions behind the handle rearwardly after fastening the wires to the conductors 13 and 14 by the screws 17 and 16, the insulator and washer are drawn into the bore of the socket, in doing which the notch 27 in the insulator clears the pin and the latter enters the longitudinal groove 31 of the insulator.

When the forward end of the handle is then slipped over the rear end of the shell 6, the pin 21 passes into the entrance slot to the forward end of the latter, after which a rotational movement of the handle brings the pin into the transverse slot. During this attaching, the spring, which is of a greater normal length than the distance between the washer and the rear end of the main portion of the bore in the handle, is considerably compressed and tends to force the handle rearwardly. Hence a relaxing of the forward pressure on the handle causes the pin to seat in the slot enlargement 28.

Since the pin 21 also extends into the groove 31 in the insulator, this pin interlocks the insulator with the handle, so that the two rotate together and so that the position of the pin with respect to the socket shell determines the position of the two conductors 13 and 14. When the pin is seated in the slot enlargement 28, these conductors are in the position of Fig. 5, with their forward ends respectively engaging the lamp bulb terminals 2 and 3 and hence closing the circuit through the lamp filament. However, when the handle is rotated to seat the pin in the companion enlargement 32, the insulator is rotated a quarter turn, bringing the two conductors to the position shown in dotted lines in Fig. 6 or out of engagement with the lamp bulb terminals and hence opening the circuit. Hence I secure the needed switching action with a simple and inexpensive construction which facilitates both the manufacture and the wiring of my socket and which requires no auxiliary fastening element for holding the several parts in proper relation to one another.

However, while I have illustrated and described my invention in an embodiment including numerous desirable details of construction and arrangement, I do not wish to be limited to these, since changes might obviously be made without departing either from the spirit of my invention or from the appended claims.

I claim as my invention:

1. For use with a lamp bulb having two terminals on its base end, a switching socket comprising a tubular shell provided at its forward end with means for interlocking it with the base of the lamp bulb and having more rearwardly a circumferential slot, a handle having a bore extending into it from its forward end and entered by the rear end of the said shell; a body member comprising an insulator extending into the shell from the rear end thereof and a pair of spaced conductors extending longitudinally of the insulator through the latter, the insulator having a longitudinal groove on one side thereof; a pair of circuit wires secured respectively to the two conductors and ex-

tending through the handle, a pin fast on the handle and extending transversely of the handle into the bore thereof through the said circumferential slot and into the groove 5 in the insulator, and spring means interposed between the handle and the insulator for pressing the insulator forwardly; the said spring means comprising a washer bearing against the rear end of the insulator 10 and having a pair of spaced perforations through which the wires respectively extend, and a compression spring disposed within the handle behind the washer.

2. For use with a lamp bulb having a 15 basal terminal, a lamp socket including a shell interlocked with the lamp bulb against relative rotation and provided with a circumferential slot, an insulator rotatable within the shell and having a lateral recess, a circuit 20 terminal carried by the insulator and movable into and out of contact with the said basal terminal by a partial rotation of the insulator, a hollow handle member rotatable on the shell and including a pin projecting 25 radially inward of the handle member through the circumferential slot in the shell

and into the lateral recess in the insulator, a compression spring disposed within the handle member and retained therein by engagement with the pin, and a washer interposed between the spring and the insulator. 30

3. A lamp socket as per claim 2, in which the handle has a metal tube lining its bore and through which the pin extends; and in which the insulating means comprise a washer 35 slidable within the said lining and bearing against the rear end of the insulator and through which washer the wires extend, and a compression spring interposed between the washer and a more rearward portion of the handle. 40

4. A lamp socket as per claim 2, in which the spring is spiral and adapted to be twisted past the pin when inserting the spring in the handle, and in which the washer has a 45 peripheral recess adapted to clear the pin so as to permit the insertion of the washer past the pin into the handle.

Signed at Chicago, Illinois, November 7th, 1925.

WILLIAM LESCHMAN.
